UNITED STATES PATENT OFFICE.

OSCAR J. LAISY, OF CLEVELAND, OHIO.

COLLAPSIBLE FORM.

Application filed April 20, 1921, Serial No. 462,805. Renewed December 26, 1924.

To all whom it may concern:

Be it known that I, OSCAR J. LAISY, a citizen of the United States, residing at Cleveland, in the county of Cuyahoga and State of Ohio, have invented a certain new and useful Improvement in Collapsible Forms, of which the following is a full, clear, and exact description, reference being had to the accompanying drawings.

10 This invention relates to collapsible forms and has particular reference to that class of forms such as are used in connection with lighter than air craft commonly known as dirigibles, although in its broadest sense my invention is capable of other uses wherein a collapsible form is advantageous and desirable.

Some of the objects of the present invention are to provide a supporting structure 20 for the gas bag of a dirigible which may be easily and conveniently collapsed to facilitate storage or shipment thereof; to provide a form or structure for the gas bag of a dirigible which shall have the advantages 25 of a rigid type of dirigible but which may be collapsed to secure the advantages of a non-rigid type of dirigible; to provide a structure of the aforesaid character which shall be simple in construction, inexpensive 30 to manufacture and easy to operate, while further objects and advantages will appear as the description proceeds.

In the accompanying drawings wherein I have shown one embodiment of my invention, but without intent to limit myself thereto, Fig. 1 is a longitudinal sectional view of a gas bag of a dirigible supported by a structure constructed in accordance with my invention; Fig. 2 is a similar view 40 showing the structure collapsed; Fig. 3 is a transverse sectional view taken on the line 3—3 of Fig. 1; Fig. 4 is an enlarged detail sectional view illustrating a method of sealing the gas bag at the end where the 45 structure is operated; and Figs. 5, 6 and 7 are detail views illustrating the manner of securing the longitudinal and transverse members together.

Broadly considered, the invention consists 50 of two series of longitudinal ribs, one series being adapted to move in unison with respect to the other to erect or collapse the structure. Suitable means are employed for spacing the ribs and means are also pro-

vided for retaining the structure in erected 55 condition.

In the drawing accompanying and forming a part of this application, 1 indicates a series of longitudinal ribs which are movable with respect to a second longitudinal 60 series indicated at 2, said ribs being shown in the present instance arranged alternately to describe a cylinder tapering at each end, although it will be understood that other shapes can be constructed to operate in a 65 manner similar to that to be described hereinafter. The ribs 1 are pivotally fastened at their respective ends to a plate 3 and a ring 7, while ribs 2 are fastened at one end to a plate 5 secured to a longitudinally disposed rod 6 and at the other end said ribs are secured to a plate 4. The ring 7 is adapted to fit within a groove 8 formed in plate 4, when the structure is erected. In order that the ribs 1 and 2 may be spaced 70 correctly when erected I provide a series 75 of transverse segmental ribs 10 therebetween. By referring to Figs. 5, 6 and 7 it will be seen that each of the ribs 1 and 2 is fitted with a sleeve 11 which is provided 80 with a depending projection 12, said sleeves being positioned on said ribs at points where the transverse ribs 10 abut. Each transverse segmental rib 10 is cut away at its 85 diagonal end as indicated at 14 and each end is fitted with a metal binding piece 15. It will be noted in this connection that the 90 cuts 14 are made in such manner that a pair of segments 10 positioned, one on each side of a longitudinal rib will have said cuts arranged in the same relative position, so that a wire 16 or other suitable tying material may be passed through one cut-away portion and around the projection 12 and up through the cut-away portion on the 95 other segment to secure the ends and a hinge joint on each side of said longitudinal rib.

In order that the longitudinal ribs may be expanded to the desired diameter, I provide 100 a series of radial supporting rods 17 and 18, rods 17 being pivotally fastened at their inner ends to a series of ring plates 19 which are slidably mounted on the rod 6 and at their outer ends, said rods are each provided with an eye 20 through which the wire 16 is passed to secure said rods to the ribs 1. Rods 18 are pivotally secured at their 105

inner ends to a similar series of ring plates 21 which are securely fastened to the rod 6 and at their outer ends, said rods are pivotally secured by the tie wires 16 to the 5 ribs 2 in a manner previously described in connection with rods 17.

From the foregoing description it will be apparent that movement of the rod 6 to the right will carry plates 21 with it and 10 collapse the radial supporting rods 17 and 18 as shown in Fig. 2. This movement also causes the segmental ribs 10 to turn about their diagonally disposed pivot points and 15 assume longitudinal positions parallel with the ribs 1 and 2.

The rod 6 is provided with a bore 6^a to receive a guide rod 25 which projects from the plate 3 and at its rear end said rod is provided with a plate 26 which has a series 20 of apertures 27 arranged circumferentially thereof. The plate 4 is provided with a series of studs 28 which are adapted to engage with the apertures 27 when the frame is erected and nuts 29 threaded thereon to 25 serve to retain the structure in erected condition.

The structure is erected by pushing forwardly on rod 6 which carries the plates 21 forwardly and causes rods 17 and 18 to 30 assume radial supporting positions similar to that shown in Fig. 1. The segmental ribs 10 will also be rotated by virtue of the movement of the longitudinal ribs and will assume transverse spacing positions as shown 35 in Figs. 5, 6 and 7.

In the case of a dirigible such as I have 40 illustrated in the drawing, the frame may be covered with a gas bag fabric in any approved manner, such covering being indicated generally at 30 and in order to provide a gas tight joint where the rod 6 projects through the rear end during erecting and collapsing of the frame, I provide a circular flange 31 on the rod 6 and secure a small 45 gas tight bag 32 thereabout which extends rearwardly and fastens to the inner side of plate 4. When the frame is erected said bag assumes a position as shown in Figs. 1 and 4; and when collapsed the bag is folded between the flange 31 and plate 4 as indicated 50 in Fig. 2.

While I have shown and described a collapsible frame for dirigibles it will be understood that a frame of the same general characteristics could be applied to many uses, such as concrete forms and others.

Having thus described my invention, what I claim is:—

1. A collapsible frame comprising a plurality of longitudinal ribs, certain of said ribs being movable in an opposite direction with respect to the other of said ribs, means connected to and adapted to space said longitudinal ribs, and means for moving said longitudinal ribs to cause said spacing means

to assume a longitudinal position and collapse said frame.

2. A collapsible frame comprising a plurality of longitudinal ribs arranged to enclose a transverse area of 360°, certain of said ribs being movable longitudinally with respect to the other of said ribs, transverse ribs hingedly connected to said longitudinal ribs, and means for moving said longitudinal ribs to cause said transverse ribs to 75 assume a longitudinal position and collapse said frame.

3. A collapsible frame comprising a plurality of longitudinal ribs arranged to enclose a transverse area of 360°, certain of 80 said ribs being movable longitudinally with respect to the other of said ribs, transverse ribs hingedly connected to said longitudinal ribs, radial members hingedly connected to and adapted to support said longitudinal 85 ribs, and means associated with said radial members for erecting and collapsing said frame.

4. A collapsible frame comprising two series of longitudinal supporting ribs, one series of ribs being movable and arranged alternately with respect to the other series to enclose a transverse area of 360°, a plurality of transverse segmental ribs hingedly connected to said longitudinal ribs, radial members hingedly connected to and adapted 95 to support said longitudinal ribs, and means connected to said radial members for erecting and collapsing said frame.

5. A collapsible frame comprising a plurality of longitudinal ribs arranged to enclose a transverse area of 360°, certain of 100 said ribs being movable longitudinally with respect to the other of said ribs, transverse ribs comprising a plurality of segments interspaced between said longitudinal ribs and hingedly connected therewith, radial supports hingedly connected to said movable ribs and to a movable member, and means for moving said member thereby to move 105 said supports in unison to erect and collapse said frame.

6. A collapsible frame comprising a plurality of longitudinal ribs arranged to enclose a transverse area of 360°, certain of 115 said ribs being movable longitudinally with respect to the other of said ribs, transverse ribs comprising a plurality of segments, each segment being interspaced between a pair of longitudinal ribs and hingedly connected therewith, a group of radial supports hingedly connected to said movable ribs adjacent each of said transverse ribs, a second group of radial supports hingedly connected to the other of said longitudinal ribs, and means for moving said first mentioned groups of radial supports in unison thereby to erect 120 and collapse said frame.

7. A collapsible frame comprising a plurality of longitudinal ribs arranged to 125

close a transverse area of 360° , transverse ribs hingedly connected to said longitudinal ribs, and means for collapsing said frame to cause said transverse ribs to assume a longitudinal position.

8. A collapsible frame comprising a plurality of longitudinal ribs arranged to enclose a transverse area of 360° , transverse ribs hingedly connected to said longitudinal ribs, radial members hingedly connected to and adapted to support said longitudinal ribs, and means for erecting and collapsing said frame.

9. A collapsible frame comprising two series of longitudinal supporting ribs, one series of ribs being movable and arranged alternately with respect to the other series to enclose a transverse area of 360° , a plurality of transverse segmental ribs hingedly connected to said longitudinal ribs, radial members hingedly connected to and adapted to support said longitudinal ribs, and a longitudinally disposed member connected to said radial members for erecting and collapsing said frame.

10. A collapsible frame comprising a plurality of longitudinal ribs arranged to enclose a transverse area of 360° , certain of said ribs being movable longitudinally with respect to the other of said ribs, transverse ribs comprising a plurality of segments interposed between said longitudinal ribs and hingedly connected therewith, radial supports hingedly connected to said movable ribs to a movable member, and means for retaining said member in a fixed position thereby to hold said parts in erected position.

11. A collapsible frame comprising a plurality of longitudinal ribs arranged to enclose a transverse area of 360° , certain of said ribs being movable longitudinally with respect to the other of said ribs, transverse ribs comprising a plurality of segments, each segment being interspaced between a pair of longitudinal ribs and hingedly connected therewith, a group of radial supports hingedly connected to said transverse ribs, a second group of radial supports hingedly connected to the other of said longitudinal ribs, and a longitudinally disposed member connected to and adapted to move said first mentioned groups of radial supports in unison thereby to erect and collapse said frame.

12. A collapsible frame comprising a plurality of longitudinal ribs, certain of said ribs being movable in an opposite direction with respect to the other of said ribs, rigid members connected to and adapted to space said longitudinal ribs, and means for moving said longitudinal ribs to cause said rigid members to assume a longitudinal position and collapse said frame.

13. A collapsible frame for airships, balloons and the like comprising a plurality of longitudinal ribs, connected at each end to a head, a rigid member extending longitudinally through the frame and through one of said heads, a hub carried by said rigid member, a plurality of radial supporting members hingedly connected at their inner ends to said hub and at their other ends to said longitudinal ribs, said rigid member being movable longitudinally with respect to said ribs thereby to erect or collapse said frame.

14. A collapsible frame for airships, balloons and the like comprising a plurality of longitudinal ribs connected at each end to a head, a rigid member extending longitudinally through the frame, means connected to one of said heads for supporting and guiding said member, a hub carried by said rigid member, a plurality of radial supporting members hingedly connected at their inner ends to said hub and at their outer ends to said longitudinal ribs, said rigid member being movable longitudinally with respect to said ribs thereby to erect or collapse said frame.

In testimony whereof, I hereunto affix my signature.

OSCAR J. LAISY.
